Primary Examiner — Philip S Hyder*Assistant Examiner* — Keith Frank*(74) Attorney, Agent, or Firm* — Andrus Intellectual Property Law, LLP(57) CLAIM

The ornamental design for a bottle, as shown and described.

DESCRIPTION

FIG. 1 is a front perspective view of a bottle;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view thereof showing a cap of the bottle in an alternative position.

The broken lines in FIGS. 7-8 represent subject matter that forms no part of the claimed design shown therein.
